[57] CLAIM

The ornamental design for a variable inner diameter tube support with criss-cross anchoring holes, as shown.

DESCRIPTION

FIG. 1 is a perspective view for a variable inner tube diameter tube support with criss-cross anchoring holes showing my design.

FIG. 2 is a front view.

FIG. 3 is a side view; and,

FIG. 4 is a bottom view.

The cross hatching shading applied to the holes in FIGS. 1 and 4 have been used to clearly show the slanted configuration of the openings running through the tube support.
